UNITED STATES PATENT OFFICE.

CHARLES JAMES FOX, OF LONDON, ENGLAND.

THERMOSTAT.

No. 883,008.

Specification of Letters Patent. Patented March 24, 1908.

Original application filed April 3, 1906, Serial No. 309,603. Divided and this application filed January 28, 1907.
Serial No. 354,531.

To all whom it may concern:

Be it known that I, CHARLES JAMES FOX, a subject of the King of Great Britain, and a resident formerly of 64 Watling street, in the 5 city of London, and now of 11 Queen Street Place, in the city of London, England, lieutenant colonel, have invented an Improved Thermostat, of which the following is a specification, this being a division of the application for Letters Patent for an improvement 10 in automatic fire-alarm systems filed by me in April 3, 1906, Serial No. 309,603.

The object of this invention is to provide an improved thermostat adapted to be interposed in an electric circuit containing a 15 visual or auditory alarm, whereby notice will be given when the electric circuit is closed by the thermostat on a predetermined temperature being attained.

20 The thermostat of my invention comprises horizontally disposed strips of metal adapted by their expansion in the presence of high temperatures to sag and thereby make contact with terminals, thus closing 25 the alarm circuit, the temperature at which contact is to be made being determined by the position of the terminals, which are made adjustable so that the instrument may be set to operate at any desired temperature.

30 Referring to the accompanying drawings forming part of this specification, Figure 1 illustrates the improved thermostat and electric connections for giving an audible signal, while Fig. 2 shows a three-way form 35 of the thermostat provided with two independent strips of metal.

On a base *a* is mounted a metal frame *b*, across which a horizontal strip *c* of metal is 40 stretched and secured so that, when expanded by heat it will sag downwards from its normal position and, upon the rise of temperature producing a predetermined deflection of the strip, the latter will come in contact with a terminal *d*, and complete the 45 electric circuit through the lead *e* connected with the terminal *d* and the lead *f* connected with the frame *b*.

The terminal *d* which consists of a set screw, is carried on the base *a* by an insulating support *g*, adjusted relatively to the level 50 of the strip and locked in position by means of nuts *h*, such adjustment enabling the amount of deflection of the strip to be de-

termined which is requisite to close the circuit at and therefore determining the temperature at which the alarm will be set in operation.

The thermostat shown in Fig. 2 is similar to that shown in Fig. 1, except that two strips *c* of metal are employed, each secured between 55 pillars *j* and the ends of the frame *b*, and two terminals *d* corresponding to the two strips and mounted in position on the base *a*. The three-way connections shown in Fig. 2 consists of the common return lead *k* connected 60 to the frame *b* and the two leads *e* connected 65 with the terminal.

Claims.

1. A thermostat comprising a non-metallic base, an approximately U-shaped metal 70 frame on the base and connected to one pole of an electric circuit, a horizontally disposed straight strip of metal stretched between the members of the frame and adapted to sag downwards, when expanded by heat, an 75 adjustable screw terminal connected to the other pole of the electric circuit and with which the metal strip is adapted to make contact, an insulator support carried by the base and in which the screw is mounted, nuts 80 on the screw, one on each side of the support, for adjusting and locking the terminal in position, a battery interposed in the electric 85 circuit and capable of sending a current through said circuit when the latter is closed by contact of the metal strip with the adjustable terminal, and an alarm interposed in the circuit and capable of being set in operation when the circuit is traversed by a current, 90 substantially as specified.

2. A thermostat comprising a non-metallic base, an approximately U-shaped metal 95 frame, on the base and connected with one pole of an electric circuit, pillars arranged between the members of the frame and in alignment with the ends thereof, a plurality of horizontally disposed straight strips of metal stretched across between the ends of the frame and the pillars and adapted to sag downwards, when expanded by heat, a plurality of adjustable screw terminals connected 100 to the other pole of the electric circuits and with which the metal strips are adapted to make contact, insulator supports carried by the base and in which the screws are mounted, 105 means for adjusting and locking the terminals

on the insulator supports, a battery interposed in the electric circuit and connected with a metal frame and capable of sending a current through any of the circuits when the latter are closed by contact of the metal strips with the adjustable terminals, and alarms interposed in the circuits and capable

of being set in operation when any of the circuits are traversed by a current, substantially as specified.

CHARLES JAMES FOX.
